UNITED STATES PATENT OFFICE.

HIRAM G. SEDGWICK, OF MILL VALLEY, CALIFORNIA, ASSIGNOR TO THE NATIONAL SAFETY APPLIANCE COMPANY, A CORPORATION OF CALIFORNIA.

AUTOMATIC TRAIN-STOP.

1,226,915.

Specification of Letters Patent. Patented May 22, 1917.

Application filed October 24, 1908, Serial No. 459,358. Renewed October 14, 1916. Serial No. 125,704.

To all whom it may concern:

Be it known that I, HIRAM G. SEDGWICK, a citizen of the United States of America, and a resident of Mill Valley, in the county 5 of Marin and State of California, have invented certain new and useful Improvements in Automatic Train-Stops, of which the following is a full and clear specification.

10 This invention relates to automatic vent valves and to a magnetic means for controlling the action of the same in that class of automatic railway stops in which the train-pipe is automatically vented to apply the 15 brakes when a normally-closed circuit on the locomotive is opened by suitable means on the roadbed.

The object of the present improvements is to increase the reliability of the apparatus, 20 rendering it practically impossible to permit any of the parts to become deranged or inoperative without that fact being made known to the train crew by the application of the brakes, whereby it will be impossible 25 for the train to proceed until this automatic stopping device is in perfect working order, as more fully hereinafter set forth.

In the accompanying drawings—

Figure 1 is a vertical sectional view of 30 the magnetic mechanism for actuating the pilot valve controlling the action of the vent valve, parts of the device being shown in side elevation and the wiring being shown in diagram;

35 Fig. 2 is a side elevation, partly in section, showing the weight down and the pilot valve actuated, and also showing a device for preventing the rebounding of the weight;

40 Figs. 3, 4 and 5 show similar views of modified forms of the type of device shown in Figs. 1 and 2;

Fig. 6 is a similar view of another modification.

45 Referring to Fig. 1, *a* designates a portion of the train-pipe which communicates with a cylinder *b* through one head thereof, in which cylinder is mounted a free piston *c* which normally, by its own weight, with or 50 without the assistance of a spring *d*, tends

to move toward the head of the cylinder through which the train-pipe enters thus normally closing the exhaust port *e* in the side of the cylinder. This exhaust port consists preferably of a series of holes increasing in diameter in a direction away from the train-pipe port, this arrangement being preferred as it insures the gradual application of the brakes.

The piston *c* is held in a closed position 60 under normal conditions by fluid pressure from a suitable source, namely from a steam space of the boiler or from a pressure reservoir, this pressure being communicated to a chamber above the piston by means of a 65 pipe *f* and ports *g*, *h* and *i*, the port *i* being in a pilot valve *j* slidably mounted in a suitable cylinder and the ports *g* and *h* being in the adjacent portions of the casing of the pilot valve and the cylinder *a*. The 70 spring *k* normally holds up the pilot valve or piston *j* in normal register with the ports *g* and *h*, a stop-collar *l* being provided on the stem *m* of this valve for limiting its upward movement and said stem being extended upwardly through the head of the pilot valve cylinder.

In a frame or guide *n* above the pilot valve is mounted a weight *o* which is sufficiently heavy when dropped to force the 80 pilot valve down against the action of its spring *k* and thus close the inlet port *g* and put port *h* in communication with an annular exhaust port *p* around the pilot valve and an escape port *q* in the pilot valve casing 85 and thus relieve the piston *c* of normal downward pressure and permit the train-pipe pressure to force it upwardly and open the vent port *e* and thus apply the brakes.

The weight *o* is supported upon the inner 90 ends of a pair of levers *r* pivoted in the guide frame and provided at their outer ends with armatures *s* which are normally attracted to normally energized magnets *t* included by normally-closed circuits *u* with a 95 suitable battery *v* preferably of the low tension bluestone type. The wires *w* constitute a partial shunt-circuit connected with the circuits *u* and having as its terminals the contact-brush *x* and one of the axles 100

of the locomotive, or other suitable current collectors or contacts adapted to contact with devices on the roadbed and complete this partial shunt-circuit when a danger point on the roadbed is reached.

- It will be observed that when the shunt-circuit *w* is completed the current from battery *v* will be shunted from the magnets, thus releasing the armatures *s* and allowing 10 the weight to fall and open the pilot valve in the manner set forth. The sudden dropping of the weight gives the pilot valve a sudden hammer-like blow and thus serves to dislodge it if it be stuck. An advantage of 15 this type of vent valve apparatus is that in case the normally-closed circuits *u* are disrupted the weight will drop and stop the train. It will also fall if only one of the circuits *u* is disrupted, as the weight will be 20 sufficiently heavy to fall against the magnetism of only one of the magnets. It will be observed also that if the pilot valve be allowed to fall by reason of the weakening or 25 breaking of spring *k* the brakes will be applied. The brakes will be applied also if for any reason the fluid pressure above the piston *c* is allowed to leak out sufficiently to permit the train-pipe pressure to force piston *c* upwardly.
- 30 In Fig. 2 the sides of the guide-bars are provided with teeth *a'* which are adapted to normally engage spring-actuated pawls *b'* when the weight is down and thus prevent rebound. These pawls are connected with 35 the weight-lifting rod *c'* in such manner that when the weight is lifted these pawls will be automatically withdrawn from engagement with the teeth *a'*.

- In Fig. 6 the cylinders and magnet are arranged vertically and the arm *c'* is adapted 40 to be swung upwardly by a weight, this weight being preferably formed integral with the armature *s*. In this form of device the restoring spring *k* may not be 45 needed as gravity may be relied upon to restore the pilot valve. In this form of device the spring *d* is desirable in order to keep the main piston valve *c* normally raised.

The form of apparatus shown in Fig. 3 is 50 substantially the same as that shown in Fig. 1, except as follows:

- The pilot valve *p* is arranged on top of the main valve and its port *l''* is normally closed, the valve being normally held up by 55 the spring *k*. The pipe *a''* connects to the train-pipe and the pilot valve normally closes it, but when the pilot valve is depressed by the weight the annular port *l''* will put this pipe *a''* into communication 60 with a port *b''* leading into the top of the cylinder of the main or vent valve. This vent valve is normally held up by a spring *d''* and thus normally closes the vent port *e*. When this vent valve is depressed by the

pressure of the train-pipe down upon its upper side a port *e''* in the valve will be put into communication with the vent port *e* and the brakes will be applied.

In the form shown in Fig. 5 the port *l''* is elongated so as to have communication 70 with the train-pipe *a''* at all times. When the valve is depressed this port *l''* is put into communication with side ports *e''* from whence the air escapes through a port *f''* above the vent valve and thus opens the vent 75 valve in the same manner as in Fig. 3. A screw tappet *g''* may be screwed adjustably in the bottom of the weight to regulate the distance the pilot valve shall be opened and thus determine the rapidity of opening the 80 vent valve, whereby it is possible to obtain an emergency application of the brakes or a slow or quick service application of the brakes. This is accomplished as is obvious by the amount of overlap of the ports *l''* 85 and *e''*, it being obvious that the greater the overlap the quicker will be the opening of the vent valve. With this form of device the port *e* may be a graduated one, as shown, 90 or it may be a single opening or slot.

In the form of device shown in Fig. 4 the annular port *l''* is replaced by a short port *l'''* opening out through the bottom of the valve, and the pipe *a''* is replaced by a pipe *f'''* leading from the boiler. The vent valve 95 is provided with a wide annular port *e'''* which is at all times in communication with the train-pipe *a* tapped through the side of the cylinder. In this form of the device, when the vent valve is depressed by steam 100 pressure, the port *e'''* will place the train-pipe in communication with the vent port *e*, as is obvious.

It will be observed that in all forms the armature, whether it be a weight or not, will, when released, move far enough away from the magnet to be out of its active field so that the device cannot be automatically reset but must be manually re-set.

Having thus fully described my invention, 110 what I claim as new and desire to secure by Letters Patent, is:—

1. In an automatic train stop, a vent valve and means for opening the same, magnetic devices normally holding said opening means inoperative, these devices including a closed circuit and said opening means embodying, 115 a pilot valve, a weight which when freed will deliver an impact or hammer blow to said pilot valve and thus operate it, and devices under control of the magnetic devices for holding said weight out of action.

2. In a train stop, the combination with a fluid pressure air brake system, a vent valve 120 for the train pipe and means for normally holding it closed, and a fluid pressure pilot valve for actuating said vent valve, said pilot valve being provided with a projecting

stem, and means for opening the pilot valve by impact or hammer blow, said means consisting of a weight tending to move toward the stem of said pilot valve, and electromagnetic means for holding the weight against said tendency and for releasing the weight to permit it to strike the stem with a hammer blow.

In testimony whereof I hereunto affix my signature in the presence of two witnesses to this 8th day of October, 1908.

HIRAM G. SEDGWICK.
